UNITED STATES PATENT OFFICE.

LOUIS S. FLATAU, OF PITTSBURG, TEXAS, ASSIGNOR TO B. F. AVERY & SONS,
OF LOUISVILLE, KENTUCKY.

SULKY-PLOW.

SPECIFICATION forming part of Letters Patent No. 482,943, dated September 20, 1892.

Application filed June 22, 1892. Serial No. 437,560. (No model.)

To all whom it may concern:

Be it known that I, LOUIS S. FLATAU, of Pittsburg, in the county of Camp and State of Texas, have invented certain new and useful Improvements in Sulky-Plows; and I do hereby declare that the following is a full, clear, and exact description of the same, reference being had to the accompanying drawings, forming part of this specification.

- 10 As is well understood by those familiar with the manufacture and use of sulky-plows, it is common and necessary to build the sulky or carriage on which the driver of the team rides and from the frame of which the plow (of one or another species) is suspended or depends so that the wheels can be set and used either in nearly or quite vertical planes—*i. e.*, with their axes horizontal—after the fashion of all carriage or cart wheels, or with 15 one wheel (that one which has to run or travel in the furrow) “canted” or set at a very considerable angle or degree of obliquity, so that that portion of the wheel’s rim which rests on the ground does so at a point under that 20 side of the sulky-frame to which said canted wheel is attached. In sulky-plows heretofore thus made with one wheel to cant, the means by which the canting of the wheel has been rendered possible have been such as to involve 25 a considerable weight of metal and a corresponding expense in the manufacture of the implements, besides having been quite complicated in construction, and hence not always easy of manipulation or management 30 by the ordinary farm-hand, who is usually unskilled in mechanics. I propose to provide for use a cant-wheel sulky-plow (or plow-carriage) which, while it shall be exceedingly light, efficient, and durable with reference to 35 the wheel-canting devices of the carriage, shall have these devices so very simple in construction and mode of operation that the farmer most unskilled in handling tools or performing any machine-work cannot fail to 40 readily manage or manipulate the wheel-canting mechanism or devices of my improved carriage.

To these main ends and objects my present invention may be said to consist, essentially, 45 in the novel construction of wheel-canting device for sulky-plows, which will be found here-

inafter fully described, and that will be found most particularly pointed out in the claim of this specification.

To enable those skilled in the art of making and familiar with the use of sulky-plows to understand and practice my invention, I will now proceed to more fully describe the same, referring by letters to the accompanying drawings, which form part of this specification, and in which I have shown my improvement carried into effect in precisely that form of machine in which I have so far practiced it, though more or less modification may be made without departing from the principle of construction and mode of operation peculiar to my improved canting device.

In the drawings, Figure 1 is a perspective view of an approved form of sulky-plow known in the market as “Avery’s Simple Sulky or Universal Plow Carriage,” having my improvement embodied therein. Fig. 2 is a partial back view of the same with the wheels set straight. Fig. 3 is a view similar to Fig. 2, but with the furrow-wheel canted.

In the several figures the same part will be found always designated by the same letter of reference.

A is the frame, B the tongue or pole, C the driver’s seat, and E G the two wheels, of a sulky-plow carriage of the type alluded to provided with all the usual devices or details of construction, which need not be herein particularized, while F is the beam, and I the mold-board, of an ordinary plow attached in a well-known manner to the saddle, with which the lower bail-like portion of the sulky-frame is provided.

G is the furrow-wheel, that is adapted to be canted or set inclined underward of the carriage at the lowermost or contacting portion of its periphery.

To render the wheel capable of being set to run in either a vertical plane, as seen at Fig. 2, or in a canted condition or oblique plane, as shown at Fig. 3, I construct the carriage in the following manner: The vertical portion or leg of the frame A at one side of the latter has its lower end formed or arranged at an angle from the perpendicular, as seen at *l*, said inwardly-inclined depending portion *l* being of course formed with an oblong aper-

- ture, through which passes the axle or shaft *m*, on which is mounted the hub *k* of the wheel *G*, and at each side of the inclined device *l* is arranged on the axle *m* a collar or 5 washer-like device, such as shown at *o* and *p*, each of which is triangular in shape in vertical central cross-section. The outer wedge-shaped washer *o* is confined between the inclined device *l* on one side and a shoulder of 10 the wheel-axle *m* on the other, while the inner collar *p* fits and bears at its outer surface against the inclined device *l* and is confined between it and a nut *s*, which is applied to the inner threaded end of the wheel-axle. 15 In the use or operation of my improved machine when the axle *m* and its accompanying collars or washers *o* *p* are all adjusted and securely clamped or fastened together by means of nut *s* in the positions shown in Fig. 2, the 20 furrow-wheel *G* is set and works like the other wheel.
- Whenever it may be desired to cant the wheel, so as to have it run in the furrow after the fashion illustrated at Fig. 3, it is only 25 necessary to loosen the nut *s*, turn the washers *o* *p* around on the axle a half-turn, and then, with the axle changed to the position in which it is shown at Fig. 3, again tighten up the nut *s*.
- 30 It will be observed that by reason of the peculiar angling or inclined shape of the part *l* of the frame at the furrow side of the carriage and the combination therewith, and with the wheel-axle *m* of the wedge-shaped 35 washers *o* *p* arranged and operating as specified, I am enabled, with the use simply of the supplemental devices *o* *p* (which weigh only a few ounces) to render the carriage capable of use with its furrow-wheel *G*, set either as seen 40 at Fig. 2 or as shown at Fig. 3; and it will be seen that inasmuch as the shifting or adjusting of the machine from one to the other

of the two necessary conditions requires only the manipulation hereinbefore explained, and involves only the use of a wrench and the 45 turning loose and tight again of the nut *s*, the farmer least skilled in the use of tools and having no experience as a mechanician can hardly fail to properly shift or adjust the wheel *G* from one to the other of its two working 50 positions, as the character of work to be done or the kind of plow being used and the nature of the land may render necessary or desirable. Of course the precise forms as well as the proportions of parts and the minor details may 55 be varied more or less without changing the novel principle of construction and mode of operation of the carriage shown and described, and hence without departing from the spirit of my invention, the gist of which rests in the 60 use together of the inclined device *l*, tapering pieces *o* *p*, and the wheel-axle, substantially as I have explained.

Having now so fully explained my novel construction of plow that those skilled in the 65 art can easily understand and practice my invention, what I claim as new, and desire to secure by Letters Patent, is—

In a sulky-plow carriage, the combination, with the frame of the carriage and the axle of 70 the furrow-wheel, of an inclined perforated portion or device *l*, the washers or collar-like devices arranged on either side of the part *l* and penetrated by the axle of the wheel, and means for clamping together rigidly the combined parts, all substantially as and for the 75 purposes set forth.

In witness whereof I have hereunto set my hand this 3d day of May, 1892.

LOUIS S. FLATAU.

In presence of—
J. E. M. FAUL,
JNO. S. FLETCHER.
